UNITED STATES PATENT OFFICE

1,932,596

MINING APPARATUS

Charles F. Osgood, Claremont, N. H., assignor to
Sullivan Machinery Company, a corporation of
Massachusetts

Application August 4, 1930, Serial No. 472,805
Renewed October 28, 1932

88 Claims. (Cl. 262—28)

This invention relates to mining apparatus and more particularly has reference to improvements in the adjustable supporting structure for the cutting appliances of an apparatus for mining 5 coal.

An object of this invention is to provide an improved mining apparatus. Another object is to provide an improved mining apparatus of the so-called combined horizontal and shear cutter 10 type. A further object is to provide an improved adjustable supporting structure for the cutting appliances of such an apparatus whereby the kerf cutter may be positioned to operate to cut kerfs in any desired horizontal plane between 15 the mine roof and mine floor and to cut vertical kerfs near the center of the entry. Another object is to provide an improved kerf cutting mechanism for a coal mining apparatus wherein a rotatable cutter head is employed for adjusting 20 the kerf cutter into horizontal and vertical cutting positions and including an improved adjustable supporting structure for the cutter head whereby the latter may be adjusted into various 25 positions between the mine roof and mine floor 30 while the head axis at all times remains parallel to the longitudinal axial line of the apparatus. A further object is to provide in an apparatus of the character set forth, an improved "parallel motion" supporting structure for the rotatable 35 cutter head. Still another object is to provide an improved driving means for the kerf cutting mechanism and improved adjusting and swinging 40 mechanisms for the kerf cutter. These and other objects of this invention will, however, hereinafter more fully appear.

In the accompanying drawings there is shown for purposes of illustration one form which the invention may assume in practice.

In these drawings,—

Fig. 1 is a side elevational view of the illustrative embodiment of the improved mining apparatus;

Fig. 2 is an enlarged plan view of the cutting mechanism and the improved adjustable supporting structure therefor, parts being shown in section to illustrate structural details;

Fig. 3 is an enlarged sectional view taken substantially on line 3—3 of Fig. 2;

Fig. 4 is a horizontal sectional view taken substantially on line 4—4 of Fig. 3;

Fig. 5 is a vertical sectional view taken substantially on line 5—5 of Fig. 3;

Fig. 6 is a detail sectional view taken substantially on line 6—6 of Fig. 2;

Fig. 7 is a detail view taken on line 7—7 of Fig. 6; and

Fig. 8 is a transverse vertical sectional view taken substantially on line 8—8 of Fig. 2.

In this illustrative embodiment of the invention there is shown a coal mining apparatus of the so-called combined horizontal and shear cutter type adapted to operate while supported and guided by the mine trackway and generally comprising a truck 1, kerf cutting mechanism 2, and an improved adjustable supporting structure generally designated 3 for the cutting mechanism. The truck 1 is mounted on wheels 4 adapted to travel along a mine trackway 5. Carried by the truck is a motor 6 which is adapted to drive through mechanism generally similar to that disclosed in the patent to Oldroyd 1,460,075, the truck wheels and through improved connections, hereinafter described, the cutting mechanism and the adjusting mechanism therefor. If desired the truck body may be mounted on a turntable in the manner described in the Oldroyd Patent 1,460,077, or in the manner described in my copending application Ser. No. 440,310, filed March 31, 1930 to enable the cutting mechanism to operate at either side of the trackway. The truck body may also be provided with suitable elevating mechanism so that the cutting mechanism may be adjusted into different elevated positions relative to the truck wheels, for instance, power elevating mechanism of the same general character as that disclosed in my copending application Ser. No. 432,541, filed March 1, 1930 and Ser. No. 409,564, filed November 25, 1929.

In the present construction, formed integral with the forward end of the truck body are parallel longitudinal frame portions or side walls 8, 8 which herein form a rigid head. Journaled within these frame portions or side walls 8 is a transverse hinge shaft 9 arranged with its axis horizontal. Pivotedly mounted at its rear end on the hinge shaft 9 is a main supporting link member or arm 10 and this link member has pivoted connection at its front end with a transverse shaft 11 connected to the cutter supporting frame 12. A secondary link member or arm 13 arranged substantially parallel with the link 10 is pivotally connected at its ends to transverse hinge shafts 14 and 15 respectively connected to the side walls 8 and cutter supporting frame 12. Mounted on the support 12 for rotation relative thereto about a longitudinal axis is a cutter head generally designated 16. The links 10 and 13 cooperate to form a "parallel motion" structure for the cutter head 16 whereby the latter may be adjusted 110

at any desired position between the mine roof and mine floor while the head axis is maintained parallel to the longitudinal axial line of the apparatus. This "parallel motion" structure may 5 be generally similar to that disclosed in the patent to Oldroyd 1,460,076, the improvement herein from one aspect residing in the mounting of the parallel links on a rigid head and the rotating cutter head on the outer ends of the links thereby 10 enabling the link structure to be made extremely heavy and strong due to the elimination of the rotating neck frame and all complicated mechanism for rotating bodily the comparatively heavy link structure relative to the truck.

15 Now referring to the specific cutting mechanism, it will be noted that the support 12 has attached thereto a cylindrical bearing sleeve 17 and rotatably mounted on this sleeve is a cylindrical supporting frame 18 having an inwardly 20 directed annular retaining flange 19 and attached to the cutter head frame 20. Mounted on the cutter head frame for rotation about an axis at right angles to the axis of the cutter head is a cylindrical supporting frame 21 rotatably mounted 25 in a bore 22 formed in the cutter head frame. A thrust ring 23 attached to the cutter head frame retains the frame 21 in its bore. Attached to the frame 21 is a support or hanger 24 which carries the cutter bar 25. Mounted for orbital movement 30 on the margin of the cutter bar 25 is a usual cutter chain 26 carrying usual cutting appliances.

The mechanism for actuating the cutter chain comprises a shaft 27 connected to the motor shaft 25 and carrying at its forward end a bevel pinion 28 meshing with a bevel gear 29 loosely mounted on the hinge shaft 9. Meshing with the bevel gear 29 is a bevel gear 30 fixed to a shaft 31 suitably journaled in bearings 32 carried by the link member 10, as clearly shown in Fig. 2. The forward end of the shaft 31 carries a bevel pinion 33 meshing with a bevel gear 34 loosely mounted on the hinge shaft 11. Meshing with the bevel gear 34 is a bevel gear 35 (see also Figs. 3 and 4) 40 fixed to a shaft 36 extending along the axis of the rotatable cutter head 16. This shaft 36 is journaled at its ends within the support 12 and cutter head frame 20 as shown in Fig. 3. Herein fixed to the front end of the shaft 36 is a bevel pinion 37 meshing with a large bevel gear 38 45 journaled on a shaft 39 arranged with its axis coincident with the axis of bar swing. The shaft 39 drives a sprocket 40 which in turn engages and drives the cutter chain 26 in a well-known manner. The gear 38 is connectible to the shaft 39 by a sliding jaw clutch 41 having a usual clutch shipper 42 operated by a handle 43. It will thus be seen that irrespective of the adjusted position of the cutter head relative to the truck, the cutter chain 26 may at all times be 50 driven and that by simply releasing the clutch 41 the cutter chain may remain idle during running of the motor.

Now referring to the improved mechanism for 55 effecting swinging of the cutter bar about its pivotal axis relative to the cutter head it will be noted that fixed to the shaft 39 and driven thereby is a bevel pinion 45 constantly meshing with reversely rotatable bevel gears 46, 47 loosely journaled on a transverse shaft 48 in turn suitably journaled within the cutter head frame 20. The reverse bevels 46, 47 are selectively connectible to the shaft 48 by means of multiple disc clutches 49 and 50 respectively, of a usual 60 design operated by a suitable shipper mechanism

51 controlled by a handle 52. Connectible to the shaft 48 is a worm 53 meshing with a worm wheel 54 fixed to a shaft 55 arranged parallel with the shaft 39 and likewise journaled in the cutter head frame. Also fixed to the shaft 55 is a spur pinion 56 meshing with the teeth of an internal gear 57 herein formed integral with the cylindrical supporting frame 21 for the cutter bar 25. The worm 53 is connectible to the shaft 48 by a sliding clutch element 58 and cooperating clutch elements 59 and 60 carried by the worm and shaft respectively. The sliding clutch element 58 is provided with usual shipper mechanism 61 operated by a handle 62. It will thus be seen that depending upon which friction clutch 49, 50 is applied the cutter bar may be swung about its pivot at a speed appropriate for cutting in either of opposite directions. The improved mechanism for rotating the cutter head 16 about its axis relative to the supporting structure 3 herein comprises a worm 63 connectible to the shaft 48 and meshing with a worm wheel 64 fixed to a longitudinally extending shaft 65 arranged parallel with the shaft 36. This shaft is suitably journaled within the cutter head frame 100 and carries a pinion 66 meshing with the teeth of an internal gear 67 herein formed integral with the cylindrical bearing sleeve 17 on which the cutter head 16 is rotatably mounted. The worm 63 is connectible to the shaft 48 by a 105 sliding clutch element 67 cooperating with clutch elements 68 and 69 carried by the worm and shaft respectively. This sliding clutch element is provided with usual shipper mechanism 70 operated by a handle 71. It will therefore be evident that the cutter head may be rotated about its axis in either of opposite directions under the control of friction clutches 49, 50. The worm gearings 53, 54 of the bar swinging mechanism and 63, 64 of the head rotating mechanism are 110 self-locking, and upon release of the clutches 61, 67 maintain automatically the cutter bar and head in their positions of adjustment.

Mechanism is provided for adjusting the supporting structure 3 by power to vary the elevation of the cutter head 16 and herein comprises a worm 75 herein connectible by a sliding jaw clutch 76 to the shaft 27. The clutch 76 is provided with usual shipper mechanism 77 operated by a handle 78. The worm 75 meshes 120 with worm wheels 79 and 80 fixed to parallel vertically extending shafts 81 and 82 respectively. These shafts are suitably journaled within the truck body and have fixed thereto at their upper ends spur pinions 83 and 84 respectively, 125 meshing with spur gears 85 and 86 fixed to parallel vertically extending shafts 87 and 88 respectively, likewise suitably journaled within the truck body. Fixed to the shafts 87, 88 are worms 89 and 90 meshing with the teeth of worm gear 130 segments 91 and 92 respectively, herein formed integral with the link member 10. Thus it will be seen that when the clutch 76 is connected to the link member 10 may be swung upwardly and downwardly about its hinge, depending upon the 135 direction of motor rotation, through the worm gearing 77, 79, 80, shaft 81, 82, spur gearing 83, 84, 85, 86, shaft 87, 88, and worms 89 and 90 meshing with the worm gear segments secured to the link. The teeth of the worms 89, 90 and 140 the worm gear segments are self-locking and automatically maintain upon release of the clutch 76, the link 10 in its different adjusted positions.

As shown most clearly in Fig. 7, the ends of the hinge shaft 14 which project within the bear- 145

ing portions at the sides of the link 13 are eccentric relative to the body of the shaft so that by the turning of the shaft, true relation between said link member and the frame portions 5 8 or so-called rigid head may be slightly varied for the purpose of putting the relations of the four bearings of the parallel link structure out of true sufficient to intentionally slightly tilt the cutter head axis out of parallel relation with the 10 longitudinal axial line of the apparatus; this being at times desirable when there is a slant in the upper or lower face of the vein of coal or if there is a slight slant in the track on which the apparatus is guided. Adjustment of the 15 hinge shaft 14 is in this instance effected manually by a worm wheel 100 fixed to one end of the shaft, and meshing with this worm wheel is a worm 101 fixed to a shaft suitably journaled in a housing 102 secured to the side of the link 20 member 13. The worm shaft is provided with suitable means for the reception of a suitable wrench or other turning instrument. The worm gearing 100, 101 is self-locking and automatically retains the shaft in its different adjusted positions. It will thus be seen that the cutter bar 25 may be tilted about an axis transverse to its length as desired.

The general mode of operation of the improved mining apparatus is as follows: The apparatus is 30 propelled about the mine at a relatively high transport speed under the propulsion of the truck wheels, while the truck wheels are driven at a relatively slow speed appropriate for cutting to propel the apparatus bodily along the trackway 35 to effect sumping and withdrawal movements of the cutter bar in the manner clearly described in the Oldroyd Patent 1,460,075. The cutter head 16 may be adjusted in any desired position between the mine roof and mine floor simply by 40 connecting the clutch 76 to effect swinging of the link member 10 about its hinge, the link member 13 cooperating with the link 10 to form a "parallel motion" structure to maintain the axis of the cutter head at all times parallel to the longitudinal axial line of the apparatus. The cutter bar 45 25 may be adjusted to any desired position about the head axis simply by connecting the clutch 67 and applying one or the other of friction clutches 49, 50. The cutter chain may be connected in 50 driving relation to the motor at will simply by connecting the clutch 41. The cutter bar 25 may be swung about its pivot relative to the cutter head by connecting the clutch 58 and applying one or the other of the friction clutches 49, 50. It will thus be seen that the cutter bar may be 55 positioned to cut horizontal kerfs above and below the head axis and vertical kerfs at either side of the head axis and in any desired intermediate position. As the operation of a mounted track cutter is well-known to those skilled in the art detailed description of the various operations of the apparatus is considered unnecessary other than to state that a horizontal kerf may be cut in accordance with the arc wall method at the 60 level of the mine bottom in front of the end of the trackway, that horizontal kerfs may be cut at the level of the mine roof and that vertical or shear cuts may be made near the center of the entry.

As a result of this invention it will be noted 65 that an improved mining apparatus is provided having an improved adjustable supporting structure for the rotatable cutter head whereby the latter may be easily adjusted into any desired position between the mine roof and mine floor. It 70 will further be noted that providing the improved

"parallel motion" structure for the rotatable cutter head all complicated adjusting mechanism is eliminated, and that by mounting the improved supporting structure on a rigid head it is possible to make the parts comparatively heavy and 75 strong due to the elimination of the rotating neck structure by which the adjusting parallel link structure was heretofore carried and the mechanism for rotating the neck structure. It will further be noted that the improved mining apparatus may operate in accordance with the arc 80 wall method to cut kerfs at the level of the mine bottom in advance of the front end of the trackway, to cut at the level of the mine roof or vertical kerfs adjacent the center of the entry. These 85 and other uses and advantages of the improved mining apparatus will be clearly apparent to those skilled in the art.

While there is in this application specifically described one form which this invention may assume in practice, it will be understood that this form of the same is shown for purposes of illustration and that the invention may be modified and embodied in various other forms without departing from its spirit or the scope of the appended claims.

What I claim as new and desire to secure by Letters Patent is:

1. In a mining apparatus, a portable support, a kerf cutter adjustable into horizontal and vertical cutting positions, an adjustable supporting structure at one end plurally articulated to said support and at its other end supporting said kerf cutter for adjustment into parallel horizontal planes, said kerf cutter being adjustable relative 105 to said supporting structure into aforesaid cutting positions, and means for adjusting said supporting structure about its plural articular connections with said support to effect aforesaid adjustment of said kerf cutter into parallel horizontal planes. 110

2. In a mining apparatus, a portable support, a frame, a rotatable cutter head mounted on said frame for rotation relative thereto, a kerf cutter pivotally mounted on said cutter head, an adjustable supporting structure at one end plurally articulated to said support about parallel axes extending transversely of said support and at its other end supporting said frame for adjusting said cutter head into different elevated positions, and means for adjusting said supporting structure about its plural articular connections with said support to effect aforesaid adjustment of said cutter head into different elevated positions. 125

3. In a mining apparatus, a portable support, a kerf cutter adjustable into horizontal and vertical cutting positions, and a parallel link structure intervening said support and kerf cutter and supporting the latter for adjustment into parallel horizontal planes, said kerf cutter being adjustable relative to said link structure into aforesaid cutting positions. 130

4. In a mining apparatus, a portable support, a kerf cutter adjustable into horizontal and vertical cutting positions, and a parallel link structure hinged connected to said support for adjusting said kerf cutter into parallel horizontal planes, said kerf cutter being adjustable relative to said link structure into aforesaid cutting positions. 135

5. In a mining apparatus, a portable support, a kerf cutter adjustable into horizontal and vertical cutting positions and an adjustable supporting structure between said support and kerf cutter including parallel links for adjusting said kerf cutter into parallel horizontal planes, said 140

kerf cutter being adjustable relative to said supporting structure into aforesaid cutting positions, and motor operated devices carried by said support for adjusting said supporting structure and including gear segments carried by one of said links and gears carried by said support and meshing with said gear segments.

6. In a mining apparatus, a portable support, a kerf cutter adjustable into horizontal and vertical cutting positions and an adjustable supporting structure between said support and kerf cutter including parallel links for adjusting said kerf cutter into parallel horizontal planes, said kerf cutter being adjustable relative to said supporting structure into aforesaid cutting positions, and motor operated devices carried by said support for adjusting said supporting structure and including gear segments carried by one of said links and gears carried by said support and meshing with said gear segments, said gears and gear segments being self-locking for automatically maintaining said supporting structure in its different positions of adjustment.

7. In a mining apparatus, a portable support, a rotatable cutter head, a kerf cutter pivotally mounted on said head, and an elongated adjustable supporting structure extending longitudinally of the apparatus and arranged between said support and cutter head and relative to which said head is rotatable, for swinging said cutter head upwardly and downwardly relative to said support while the head axis always remains parallel to the longitudinal axial line of the apparatus and moves during such swinging in an upright plane parallel to said longitudinal axial line.

8. In a mining apparatus, a portable support, parallel links pivotally connected to said support, a frame supported by said links, a cutter head mounted on said frame for rotation relative thereto about a horizontal axis and a kerf cutter pivotally mounted on said cutter head, and motor operated devices for rotating said cutter head about its axis and for swinging said kerf cutter about its pivot.

9. In a mining apparatus, a portable support, a kerf cutter adjustable into horizontal and vertical cutting positions, an arm pivotally connected to said support to swing in longitudinally extending vertical planes relative thereto and supporting said kerf cutter, said kerf cutter being adjustable relative to said arm into aforesaid cutting positions, devices for swinging said arm about its pivot to vary the cutting position of said kerf cutter, and devices operative when such swinging occurs with the kerf cutter adjusted for horizontal cutting to tilt the kerf cutter about an axis parallel to the arm swing pivot to maintain said kerf cutter during such adjustment parallel to a common straight line lying in a longitudinally extending vertical plane, whereby said kerf cutter may make differently elevated horizontal cuts in planes above said arm swing pivot.

10. In a mining apparatus, a portable support, a cutter head rotatable about a longitudinal axis, a kerf cutter pivotally mounted on said cutter head, an arm pivotally connected to said support to swing in longitudinally extending vertical planes relative thereto and supporting said cutter head and relative to which the latter is rotatable, devices for swinging said arm about its pivot to vary the elevation of said cutter head, and devices for maintaining the axis of said cutter head parallel to a common stationary straight line during such adjustment.

11. In a mining apparatus, a portable support, a motor carried thereby, a kerf cutter adjustable into horizontal and vertical cutting positions, an adjustable supporting structure plurally articulated at its rear end to said support and supporting at its forward end said kerf cutter for adjustment into parallel horizontal planes, said kerf cutter being adjustable relative to said supporting structure into aforesaid cutting positions, devices driven by said motor for adjusting said supporting structure about its plural articular connections with said support to effect aforesaid adjustment of said kerf cutter into parallel horizontal planes, and devices driven by said motor for actuating said kerf cutter. 90

12. In a mining apparatus, a portable support, a motor carried by said support, a frame, a rotatable cutter head mounted on said frame, a kerf cutter pivotally mounted on said cutter head, an adjustable supporting structure plurally articulated at its rear end to said support and supporting at its forward end said frame for adjusting said cutter head into different elevated positions and relative to which said cutter head is rotatable, devices driven by said motor for adjusting said supporting structure about its plural articular connections with said support to effect aforesaid adjustment of said cutter head into different elevated positions, and devices driven by said motor for actuating said kerf cutter. 95

13. In a mining apparatus, a portable support, a motor carried by said support, a frame, a rotatable cutter head mounted on said frame, a kerf cutter pivotally mounted on said cutter head, an adjustable supporting structure plurally articulated at its rear end to said support and supporting at its forward end said frame for adjusting said cutter head into different elevated positions and relative to which said cutter head is rotatable, devices driven by said motor for adjusting said supporting structure about its plural articular connections with said support to effect aforesaid adjustment of said cutter head into different elevated positions, devices driven by said motor for actuating said kerf cutter, and devices driven by said motor for rotating said cutter head about its axis relative to said supporting structure. 100

14. In a mining apparatus, a portable support, a motor carried by said support, a frame, a rotatable cutter head mounted on said frame, a kerf cutter pivotally mounted on said cutter head, an adjustable supporting structure plurally articulated at its rear end to said support and supporting at its forward end said frame for adjusting said cutter head into different elevated positions and relative to which said cutter head is rotatable, devices driven by said motor for adjusting said supporting structure about its plural articular connections with said support to effect aforesaid adjustment of said cutter head into different elevated positions, devices driven by said motor for actuating said kerf cutter, and devices driven by said motor for rotating said cutter head about its axis relative to said supporting structure and for swinging said kerf cutter about its pivot. 115

15. In a mining apparatus, a portable support, a kerf cutter adjustable into horizontal and vertical cutting positions, a parallel link structure intervening said support and kerf cutter and supporting the latter for adjustment into parallel horizontal planes, said kerf cutter being adjustable relative to said link structure into aforesaid cutting positions, a motor carried by said support, devices driven by said motor for adjusting said 120

- link structure, and devices driven by said motor for actuating said kerf cutter.
16. In a mining apparatus, a portable support, a frame, a rotatable cutter head mounted on said frame, a kerf cutter pivotally mounted on said cutter head, an adjustable supporting structure at its rear end plurally articulated to said support on parallel axes extending transversely of the support and at its forward end supporting said frame for adjusting said cutter head into different elevated positions, and motor operated devices carried by said cutter head for rotating said head about its axis.
17. In a mining apparatus, a portable support, a frame, a rotatable cutter head mounted on said frame, a kerf cutter pivotally mounted on said cutter head, an adjustable supporting structure at its rear end plurally articulated to said support on parallel axes extending transversely of the support and at its forward end supporting said frame for adjusting said cutter head into different elevated positions, and motor operated devices carried by said cutter head for rotating said head about its axis and for swinging said kerf cutter about its pivot.
18. In a mining apparatus, a portable support, a kerf cutter, an adjustable supporting structure between said support and kerf cutter including an arm pivotally connected to said support for swinging movement upon a horizontal axis extending transversely of said support, devices for swinging said arm about its pivot to vary the elevation of said kerf cutter, devices for adjusting said kerf cutter relative to said adjustable supporting structure upon a second horizontal axis to maintain said kerf cutter at all times during such adjustment in horizontal cutting position and parallel to a common straight line, and devices carried at the outer end of said arm and forwardly of said second horizontal axis for adjusting said kerf cutter about a third horizontal axis into horizontal and vertical cutting positions.
19. In a mining apparatus, a portable support, a kerf cutter adjustable into horizontal and vertical cutting positions, an adjustable supporting structure between said support and kerf cutter including an arm pivotally connected to said support to swing in longitudinally extending vertical planes for adjusting said kerf cutter into parallel horizontal planes, said kerf cutter being adjustable relative to said supporting structure into aforesaid cutting positions, and motor operated devices carried by said support for swinging said arm about its pivot including a gear segment carried by said arm and a gear carried by said support and meshing with said gear segment.
20. In a mining apparatus, a portable support, a kerf cutter, an adjustable supporting structure between said support and said kerf cutter for swinging said kerf cutter about a transverse horizontal axis extending transversely of and on said support into different elevated positions, respectively in horizontal planes adjacent the mine bottom and in higher horizontal planes adjacent said transversely extending axis, while said kerf cutter at all times remains parallel to a common straight line, and devices at the outer extremity of said supporting structure for adjusting said kerf cutter into horizontal and vertical cutting positions.
21. In a mining apparatus, a portable support, parallel links pivotally connected to said support for swinging movement in a vertical direction relative thereto, a frame supported by said links, a cutter head mounted on said frame for rotation relative thereto about a horizontal axis, and a kerf cutter pivotally mounted on said cutter head.
22. In a mining apparatus, a portable base, an arm structure pivotally mounted on the forward end of said base to swing in a vertical direction relative thereto about a horizontal axis extending transversely of said base, and a kerf cutter mounted on the outer extremity of said arm structure and adjustable relative thereto into horizontal and vertical cutting positions, said arm structure having a range of swinging movement about said transverse horizontal axis sufficient to position said kerf cutter, solely by swinging movement about such transverse horizontal axis, optionally in a horizontal position substantially on the mine bottom or in a position wholly above a horizontal plane including said transverse horizontal axis.
23. In a mining apparatus, a portable base, an arm structure pivotally mounted on the forward end of said base to swing in a vertical direction relative thereto about a horizontal axis extending transversely of said base, and a kerf cutter mounted on the outer extremity of said arm structure and adjustable relative thereto into horizontal and vertical cutting positions, a motor carried by said base, and relative to which said arm structure is swingable, and devices driven by said motor for actuating said kerf cutter.
24. In a mining apparatus, a portable base, an arm structure pivotally mounted on the forward end of said base to swing in a vertical direction relative thereto about a horizontal axis extending transversely of said base, and a kerf cutter mounted on the outer extremity of said arm structure and adjustable relative thereto into horizontal and vertical cutting positions, a motor carried by said base and relative to which said arm structure is swingable, devices driven by said motor for actuating said kerf cutter, and devices driven by said motor for adjusting said kerf cutter relative to said arm structure into aforesaid cutting positions.
25. In a mining apparatus, a portable base, an arm structure pivotally mounted on the forward end of said base to swing in a vertical direction relative thereto about a horizontal axis extending transversely of said base, a cutter head mounted on the outer extremity of said arm structure for rotation relative thereto about a horizontal axis, and a kerf cutter pivotally mounted on said cutter head and rotatable therewith relative to said arm structure into horizontal and vertical cutting positions, said arm structure having a range of swinging movement about said transverse horizontal axis sufficient to position said kerf cutter, solely by swinging movement about such transverse horizontal axis, optionally in a horizontal position substantially on the mine bottom or in a position wholly above a horizontal plane including said transverse horizontal axis.
26. In a mining apparatus, a portable base, an arm structure pivotally mounted on the forward end of said base to swing in a vertical direction relative thereto about a horizontal axis extending transversely of said base, a cutter head mounted on the outer extremity of said arm structure for rotation relative thereto about a horizontal axis, a kerf cutter pivotally mounted on said cutter head and rotatable therewith relative to said arm structure into horizontal and vertical cutting positions, and mechanism for automatically maintaining the axis of said cutter head parallel to a common stationary axis.

- straight line during swinging of said arm structure about said horizontal transverse axis.

27. In a mining apparatus, a portable base, parallel arms pivotally mounted on the forward end of said base for swinging movement relative thereto about horizontal axes, and a kerf cutter mounted on the outer extremities of said arms for adjustment relative thereto into horizontal and vertical cutting positions.

28. In a mining apparatus, a portable base, parallel arms pivotally mounted on the forward end of said base for swinging movement relative thereto about horizontal axes, a kerf cutter mounted on the outer extremities of said arms for adjustment relative thereto into horizontal and vertical cutting positions, and devices for adjusting said arms out of parallel relationship to effect tilting of said kerf cutter relative to the horizontal.

29. In a mining apparatus, a portable base, parallel arms pivotally mounted on the forward end of said base for swinging movement relative thereto about horizontal axes, and a kerf cutter mounted on the outer extremities of said arms for adjustment relative thereto into horizontal and vertical cutting positions, said arms maintaining automatically said kerf cutter parallel to a common straight line during swinging of said arms about their pivots relative to said base.

30. In a mining apparatus, a portable base, parallel arms pivotally mounted on the forward end of said base for swinging movement relative thereto about a horizontal axis, a cutter head mounted on the outer extremities of said arms for rotation relative thereto about a horizontal axis, and a kerf cutter pivotally mounted on said cutter head and rotatable therewith relative to said arms into horizontal and vertical cutting positions.

31. In a mining apparatus, a portable base, parallel arms pivotally mounted on the forward end of said base for swinging movement relative thereto about a horizontal axes, a cutter head mounted on the outer extremities of said arms for rotation relative thereto about a horizontal axis, a kerf cutter pivotally mounted on said cutter head and rotatable therewith relative to said arms into horizontal and vertical cutting positions, and devices for adjusting said arms out of parallel relationship to effect tilting of said kerf cutter relative to the horizontal.

32. In a mining apparatus, a portable base, parallel arms pivotally mounted on the forward end of said base for swinging movement relative thereto about horizontal axes, a cutter head mounted on the outer extremities of said arms for rotation relative thereto about a horizontal axis, and a kerf cutter pivotally mounted on said cutter head and rotatable therewith relative to said arms into horizontal and vertical cutting positions, and said arms maintaining automatically said cutter head axis parallel to a common straight line during swinging of said arms about their pivots relative to said base.

33. In a mining apparatus, a supporting frame, a cutter head mounted on said frame for rotation relative thereto, a kerf cutter pivotally mounted on said cutter head and mechanism for rotating said head and swinging said kerf cutter and comprising a shaft journaled on said head, relatively rotatable gears coaxial with and selectively connectible to be driven by said shaft, clutches for effecting rotation of said shaft in either of opposite directions, gearing driven by one of said gears for effecting head rotation, and gearing

driven by said other gear for effecting swinging of said kerf cutter.

34. In a mining apparatus, a supporting frame, a cutter head mounted on said frame for rotation relative thereto, a kerf cutter pivotally mounted on said cutter head and mechanism for rotating said head and swinging said kerf cutter comprising a shaft journaled on said head, gears driven by said shaft, clutch devices for connecting said gears to said shaft, clutches for effecting rotation of said shaft in either of opposite directions, gearing driven by one of said gears to effect head rotation, and gearing driven by said other gear for effecting swinging of said kerf cutter.

35. In a mining apparatus, a supporting frame, a cutter head mounted on said frame for rotation relative thereto, a kerf cutter pivotally mounted on said cutter head, and mechanism for rotating said head and swinging said kerf cutter comprising a shaft journaled on said head, relatively rotatable gears coaxial with and selectively connectible to be driven by said shaft, clutches for effecting rotation of said shaft in either of opposite directions, gearing driven by one of said gears and including a stationary gear secured to said supporting frame for rotating said cutter head about its axis, and gearing driven by said other gear for swinging said kerf cutter.

36. In a mining apparatus, a portable support, parallel links pivotally connected to said support, a frame supported by said links, a cutter head mounted on said frame for rotation relative thereto about a horizontal axis, a kerf cutter pivotally mounted on said cutter head, and motor operated devices for rotating said cutter head about its axis.

37. In a mining apparatus, a portable support, parallel links pivotally connected to said support, a frame supported by said links, a cutter head mounted on said frame for rotation relative thereto about a horizontal axis, a kerf cutter pivotally mounted on said cutter head, and motor operated devices for rotating said cutter head about its axis and for swinging said kerf cutter about its pivot.

38. In a mining apparatus, a portable support, a motor, parallel links pivotally connected to said support, a frame supported by said links, a cutter head mounted on said frame for rotation relative thereto about a horizontal axis, a kerf cutter pivotally mounted on said cutter head, said cutter head being rotatable relative to said links and motor, and devices driven by said motor for rotating said cutter head about its axis.

39. In a mining apparatus, a portable support, a motor, parallel links pivotally connected to said support, a frame supported by said links, a cutter head mounted on said frame for rotation relative thereto about a horizontal axis, a kerf cutter pivotally mounted on said cutter head, said cutter head being rotatable relative to said links and motor, and devices driven by said motor for rotating said cutter head about its axis and for swinging said kerf cutter about its pivot.

40. In a mining apparatus, a portable support, a parallel link structure pivotally connected to said support, a frame supported by said link structure, a cutter head mounted on said frame for rotation relative thereto about a horizontal axis, a kerf cutter pivotally mounted on said cutter head, and mechanism for adjusting said parallel link structure and acting to apply pressure to the same portion thereof during swing

- in opposite directions to move said cutter head into different operative positions while said head axis is always maintained parallel to a common straight line.

5. 41. In a mining apparatus, a portable base, an arm structure pivotally mounted on said base to swing relative thereto, a frame supported on the outer extremity of said arm structure and to which said arm structure is pivotally connected upon an axis perpendicular to the planes of swinging movement of said arm structure, said frame being swingable relative to said arm structure, a cutter head mounted on said frame for rotation relative thereto about a horizontal axis, a kerf cutter pivotally mounted on said cutter head for swinging movement relative thereto, and motor operated devices for rotating said cutter head about its axis and for swinging said kerf cutter about its pivot.

10. 42. In a mining apparatus, a portable base, an arm structure pivotally mounted on said base to swing relative thereto in vertical planes, a frame supported on the outer extremity of said arm structure and to which said arm structure is pivotally connected, said frame being swingable relative to said arm structure, a cutter head mounted on said frame for rotation relative thereto about a horizontal axis, a kerf cutter pivotally mounted on said cutter head for swinging movement relative thereto, motor operated devices for rotating said cutter head about its axis and for swinging said kerf cutter about its pivot, and motor operated means for swinging said arm structure relative to said base.

15. 43. In a mining apparatus, a portable base, an arm structure pivotally mounted on said base to swing relative thereto in vertical planes, a frame supported on the outer extremity of said arm structure and to which said arm structure is pivotally connected, said frame being swingable relative to said arm structure, a cutter head mounted on said frame for rotation relative thereto about a horizontal axis, a kerf cutter pivotally mounted on said cutter head for swinging movement relative thereto, motor operated devices for rotating said cutter head about its axis and for swinging said kerf cutter about its pivot, motor operated means for swinging said arm structure relative to said base, and motor operated means for moving said base over the mine floor to effect feeding of said kerf cutter into the material to be cut.

20. 44. In a mining apparatus, a portable base, an arm structure pivotally mounted on said base to swing relative thereto, a frame supported on the outer extremity of said arm structure and to which said arm structure is pivotally connected, said frame being swingable relative to said arm structure, a cutter head mounted on said frame for rotation relative thereto about a horizontal axis, a kerf cutter pivotally mounted on said cutter head for swinging movement relative thereto, and motor operated devices for rotating said cutter head about its axis and for swinging said kerf cutter about its pivot, said head rotating and kerf cutter swinging devices including a motor supported on said base and relative to which said arm structure is swingable.

25. 45. In a mining apparatus, a portable base, an arm structure pivotally mounted on said base to swing relative thereto in vertical planes, a frame supported on the outer extremity of said arm structure and to which said arm structure is pivotally connected, said frame being swingable relative to said arm structure, a cutter head mounted on said frame for rotation relative thereto about a horizontal axis, a kerf cutter pivotally mounted on said cutter head for swinging movement relative thereto, motor operated devices for rotating said cutter head about its axis and for swinging said kerf cutter relative to said cutter head in any position of said cutter head about its axis.

30. 46. In a mining apparatus, a portable support, parallel links pivotally connected to said support for swinging in upright planes, a frame supported by said links, a cutter head mounted on said frame for rotation relative thereto about a horizontal axis extending longitudinally of the apparatus, and a kerf cutter pivotally mounted on said cutter head, said parallel links maintaining said cutter head axis always parallel to a common straight line during swinging of said links about their pivots.

35. 47. In a mining apparatus, a portable base, an arm structure pivotally mounted on said base for swinging movement relative thereto, a frame supported on the outer extremity of said arm structure and to which the latter is pivotally connected upon an axis perpendicular to the planes of swinging movement of said arm structure, said frame being swingable relative to said arm structure, a cutter head supported by said frame for rotation relative thereto about a horizontal axis, a kerf cutter mounted on said cutter head and adjustable with said head into horizontal and vertical cutting positions, and motor operated devices for rotating said head about its axis and for driving said kerf cutter.

40. 48. In a mining apparatus, a portable base, an arm structure pivotally mounted on said base for swinging movement relative thereto, a frame supported on the outer extremity of said arm structure and to which the latter is pivotally connected upon an axis perpendicular to the planes of swinging movement of said arm structure, said frame being swingable relative to said arm structure, a cutter head supported by said frame for rotation relative thereto about a horizontal axis, a kerf cutter pivotally mounted on said cutter head and adjustable with said head into horizontal and vertical cutting positions, a motor on said base, and connections driven by said motor and connected to said cutter head and kerf cutter for rotating said cutter head about its axis and for swinging said kerf cutter and including connections extending along and supported by said arm structure.

45. 49. In a mining apparatus, a portable base, an arm structure pivotally mounted on said base for swinging movement relative thereto, a frame supported on the outer extremity of said arm structure and to which the latter is pivotally connected upon an axis perpendicular to the planes of swinging movement of said arm structure, said frame being swingable relative to said arm structure, a cutter head supported by said frame for rotation relative thereto about a horizontal axis, a kerf cutter pivotally mounted on said cutter head and adjustable with said head about the head axis into horizontal and vertical cutting positions, motor operated devices for rotating said cutter head about its axis, and motor operated devices for swinging said kerf cutter relative to said cutter head in any position of said cutter head about its axis.

50. 50. In a mining apparatus, a portable base, a

parallel motion arm structure overhanging said base and pivotally mounted at its rearward extremity on said base to swing in a vertical direction relative thereto, and a kerf cutter mounted 5 on the outer overhanging extremity of said arm structure and adjustable relative to said arm structure into horizontal and vertical cutting positions.

51. In a mining apparatus, a portable base, a 10 parallel motion arm structure overhanging said base and pivotally mounted at its rearward extremity on said base to swing in a vertical direction relative thereto, a cutter head mounted on the outer overhanging extremity of said arm structure for rotation relative thereto about a 15 horizontal axis, and a kerf cutter pivotally mounted on said cutter head and rotatable therewith about the head axis relative to said arm structure into horizontal and vertical cutting positions.

52. In a mining apparatus, a portable support, 15 parallel links pivotally connected to said support, a frame supported by said links, a cutter head mounted on said frame for rotation relative thereto about a horizontal axis, a kerf cutter pivotally mounted on said cutter head, and motor operated devices for rotating said cutter head about its 20 axis relative to said frame.

53. In a mining apparatus, a portable support, 20 parallel links pivotally connected to said support, a frame supported by said links, a cutter head mounted on said frame for rotation relative thereto about a horizontal axis, a kerf cutter pivotally mounted on said cutter head, and motor operated 25 devices for swinging said kerf cutter about its pivot relative to said cutter head.

54. In a mining apparatus, a portable base, an 25 arm structure overhanging said base and pivotally mounted at its rearward extremity on said base to swing in a vertical direction relative thereto about a horizontal axis extending transversely of said apparatus, a kerf cutter mounted on the outer overhanging extremity of said arm structure and adjustable relative to said arm structure into horizontal and vertical cutting positions, 30 said arm structure having a range of swinging movement about said transverse axis sufficient to position said kerf cutter, solely by such swinging of said arm structure about said transverse horizontal axis, selectively in a horizontal position substantially at the level of the mine bottom or in a position wholly above a horizontal plane including said transverse horizontal axis, and motor operated devices for adjusting said kerf cutter relative to said arm structure including a gear secured against rotation relative to said arm structure, a gear adjustable with said kerf cutter and meshing with said gear and devices adjustable with said kerf cutter for driving said last mentioned gear.

55. In a mining apparatus, a portable base, an 35 arm structure overhanging said base and pivotally mounted at its rearward extremity on said base to swing in a vertical direction relative thereto about a horizontal axis extending transversely of said apparatus, and kerf cutting mechanism including a rotatable cutter head mounted on the outer overhanging extremity of said arm structure, a kerf cutter pivotally mounted on said cutter head, said cutter head being adjustable relative to said arm structure to position said kerf cutter into horizontal and vertical cutting 40 positions, said arm structure having a range of swinging movement about said transverse axis sufficient to position said kerf cutter, solely by

such swinging of said arm structure about said transverse horizontal axis, selectively in a horizontal position substantially at the level of the mine bottom or in a position wholly above a horizontal plane including said transverse horizontal axis, and motor operated devices for adjusting said cutter head relative to said arm structure including a gear fixed against rotation relative to said arm structure, a gear journaled within said cutter head and meshing with said gear and devices carried by said cutter head for rotating said second mentioned gear.

56. In a mining apparatus, a portable base, 45 parallel links pivotally connected to said base, a frame supported by said links, a cutter head 90 mounted on said frame for rotation relative thereto about a horizontal axis extending longitudinally of the apparatus, and a kerf cutter pivotally mounted on said cutter head and adjustable with said head into different horizontal cutting positions about the head axis.

57. In a mining apparatus, a portable base, 50 parallel links pivotally connected to said base on parallel horizontal axes, a frame supported by said links, a cutter head mounted on said 100 frame for rotation relative thereto about a horizontal axis extending longitudinally of the apparatus, a kerf cutter pivotally mounted on said cutter head and adjustable with said head into different cutting positions about the head axis, 105 and a motor mounted on said base and relative to which said links are swingable for actuating said kerf cutter.

58. In a mining apparatus, a portable base, 55 parallel links pivotally connected at their rear ends to said base, a frame supported by said links and to which the forward ends of said links are pivotally connected, a cutter head mounted on said frame for rotation relative thereto about a horizontal axis extending longitudinally of the 110 apparatus, a kerf cutter pivotally mounted on said cutter head and adjustable with said head into different cutting positions about the head axis, and a motor mounted on said base and relative to which said links are swingable for 115 actuating said kerf cutter and for swinging said links relative to said base.

59. In a mining apparatus, a portable base, 60 parallel links pivotally connected to said base, a frame supported by said links, a cutter head 125 mounted on said frame for rotation relative thereto about a horizontal axis, a kerf cutter pivotally mounted on said cutter head and adjustable with said head into different cutting 65 positions about the head axis, and a motor mounted on said base and relative to which said links are swingable for actuating said kerf cutter, for swinging said links relative to said base and for rotating said cutter head.

60. In a mining apparatus, a portable base, 70 parallel links pivotally connected to said base, a frame supported by said links, a cutter head mounted on said frame for rotation relative thereto about a horizontal axis, a kerf cutter pivotally mounted on said cutter head and adjustable with said head into different cutting 75 positions about the head axis, and a motor mounted on said base and relative to which said links are swingable for actuating said kerf cutter, for swinging said links relative to said base, for rotating said cutter head and for swinging said kerf cutter relative to said head.

61. In a mining apparatus, a portable base, 80 parallel links pivotally connected to said base for swinging upon horizontal axes located in two 150

- different horizontal planes, a frame supported by said links, a cutter head mounted on said frame for rotation relative thereto about a horizontal axis, a kerf cutter pivotally mounted on said cutter head and adjustable with said head into different cutting positions about the head axis, and devices for angularly adjusting the cutter head axis relative to said links. 5
62. In a mining apparatus, a portable base, a kerf cutter adjustable into horizontal and vertical cutting positions, an arm pivotally connected to said base to swing in longitudinally extending vertical planes relative thereto and supporting said kerf cutter, said kerf cutter being adjustable relative to said arm into aforesaid cutting positions, devices for swinging said arm about its pivot to vary the cutting position of said kerf cutter and including a motor on said base and relative to which said arm is swingable, and devices for maintaining said kerf cutter parallel to a common straight line during such adjustment of said kerf cutter. 10
63. In a mining apparatus, a portable base, a cutter head rotatable about a longitudinal axis, a kerf cutter pivotally mounted on said cutter head to swing relative thereto, an arm pivotally connected to said base and supporting said cutter head and relative to which the latter is rotatable, devices for swinging said arm about its pivot to vary the elevation of said cutter head, devices for maintaining the axis of the cutter head parallel to a common stationary straight line during such adjustment, and devices for tilting said cutter head about a transverse axis relative to said arm to move the head axis out of parallelism with aforesaid straight line. 25
64. In a mining apparatus, a portable base, a parallel link structure pivotally connected to said base, a frame supported by said link structure, a cutter head mounted on said frame for rotation relative thereto about a horizontal axis extending longitudinally of the apparatus, a kerf cutter pivotally mounted on said cutter head, a motor on said base relative to which said link structure is swingable, and mechanism driven by said motor and operatively connected to apply pressure to the same link irrespective of the direction of link structure pivoting, for adjusting said parallel link structure to move said cutter head into different operative positions while said head axis is always maintained parallel to a common straight line. 40
65. In a mining apparatus, a portable base, parallel links pivotally connected to said base, a frame supported by said links, a cutter head mounted on said frame for rotation relative thereto about a horizontal axis, a kerf cutter pivotally mounted on said cutter head, said parallel links maintaining said cutter head axis always parallel to a common straight line during swinging of said links about their pivots, and devices for tilting said cutter head about a transverse axis relative to said links to move the head axis out of parallelism with aforesaid straight line. 55
66. In a mining apparatus, a portable support, parallel links pivotally connected at one end to said support, a frame supported by said links and to which the other ends of said links are pivotally connected, a cutter head mounted on said frame for rotation relative thereto about an axis disposed at right angles to the axes of swinging movement of said links, and a kerf cutter pivotally mounted on said cutter head, said parallel links maintaining said cutter head axis 70
- always parallel to a common straight line during swinging of said links about their pivots. 67. In a mining apparatus, a portable base, an arm structure pivotally mounted on said base for swinging movement relative thereto, a frame supported on the outer extremity of said arm structure and to which the latter is pivotally connected, said frame being swingable relative to said arm structure, a cutter head supported by said frame for rotation relative thereto about an axis disposed at right angles to the axis of swinging movement of said arm structure, a kerf cutter pivotally mounted on said cutter head for swinging movement relative thereto and adjustable with said head into horizontal and vertical cutting positions, a motor on said base relative to which said arm structure is angularly movable during its swinging movement, and connections driven by said motor and connected to said cutter head and kerf cutter for rotating said cutter head about its axis and for swinging said kerf cutter and including connections extending along and supported by said arm structure. 80
68. In a mining apparatus, a portable base, parallel links pivotally connected to said base, a frame supported by said links, a cutter head mounted on said frame for rotation relative thereto about an axis disposed at right angles to the axes of swinging movement of said links, a kerf cutter pivotally mounted on said cutter head and adjustable with said head into different horizontal cutting positions about the head axis, and a motor mounted on said base and relative to which said links are swingable for actuating said kerf cutter. 85
69. In a mining apparatus, a portable base, parallel links pivotally connected at one end thereof to said base, a frame supported by said links and connected pivotally to the other ends of the latter, a cutter head mounted on said frame for complete rotation relative thereto about an axis disposed at right angles to the axes of swinging movement of said links, a kerf cutter pivotally mounted on said cutter head and adjustable with said head into different cutting positions about the head axis, and a motor mounted on said base and relative to which said links are swingable for actuating said kerf cutter and for swinging said links relative to said base. 90
70. In a mining apparatus, a portable base, a parallel link structure pivotally connected to said base, a frame supported by said link structure, a cutter head mounted on said frame for rotation relative thereto about an axis disposed at right angles to the axes of swinging movement of said links, a kerf cutter pivotally mounted on said cutter head, a motor on said base relative to which said link structure is swingable, and mechanism driven by said motor and including a power connection with the same link irrespective of the direction of link adjustment for adjusting said parallel link structure to move said cutter head into different operative positions while said head axis is always maintained parallel to a common straight line. 100
71. In a mining apparatus, a portable support, a kerf cutter adjustable into horizontal and vertical cutting positions, an adjustable supporting structure at one end plurally articulated to said support on parallel axes and at its other end supporting said kerf cutter for adjustment into parallel horizontal planes, said kerf cutter being adjustable relative to said supporting structure into aforesaid cutting positions, and means for adjusting said supporting structure about its plu- 105
- 75

ral articular connections with said support to effect aforesaid adjustment of said kerf cutter into parallel horizontal planes, said kerf cutter being tilttable about a transverse axis relative to 5 the supporting structure into different angular positions relative to aforesaid horizontal planes.

72. In a mining apparatus, a portable support, a frame, a rotatable cutter head mounted on said frame for rotation relative thereto, a kerf cutter pivotally mounted on said cutter head, an adjustable supporting structure at one end plurally articulated to said support on parallel axes and at its other end supporting said frame for adjusting said cutter head into different elevated positions, and means for adjusting said supporting structure about its plural articular connections with said support to effect aforesaid adjustment of said cutter head into different elevated positions, said cutter head being tilttable 10 relative to said supporting structure about an axis extending transversely of said supporting structure to vary the angular position of the plane of cut of said kerf cutter relative to the horizontal.

73. In a mining apparatus, a portable support, a parallel link structure pivotally connected to said support to swing in a vertical direction relative thereto, a frame supported by said link structure, a cutter head mounted on said frame for rotation relative thereto about a horizontal axis, a kerf cutter pivotally mounted on said cutter head, and mechanism for adjusting said parallel link structure to move said cutter head into different operative positions while said head axis 30 is always maintained parallel to a common straight line.

74. In a mining apparatus, a portable support, parallel links pivotally connected to said support to swing in a vertical direction relative thereto, a frame supported by said links, a cutter head mounted on said frame for rotation relative thereto about a horizontal axis extending longitudinally of the apparatus, and a kerf cutter pivotally mounted on said cutter head, said 40 parallel links maintaining said cutter head axis always parallel to a common straight line during swinging of said links about their pivots.

75. In a mining apparatus, a portable base, parallel links pivotally connected to said base to swing in a vertical direction relative thereto, a frame supported by said links, a cutter head mounted on said frame for rotation relative thereto about a horizontal axis extending longitudinally of the apparatus, and a kerf cutter 55 pivotally mounted on said cutter head and adjustable with said head into different cutting positions about the head axis.

76. In a mining apparatus, a portable base, parallel links pivotally connected to said base to swing in a vertical direction relative thereto, a frame supported by said links, a cutter head mounted on said frame for rotation relative thereto about a horizontal axis extending longitudinally of the apparatus, a kerf cutter pivotally mounted on said cutter head and adjustable with said head into different cutting positions about the head axis, and a motor mounted on said base and relative to which said links are swingable for actuating said kerf cutter.

77. In a mining apparatus, a portable base, parallel links pivotally connected to said base to swing in a vertical direction relative thereto, a frame supported by said links, a cutter head mounted on said frame for rotation relative 75 thereto about a horizontal axis extending longi-

tudinally of the apparatus, a kerf cutter pivotally mounted on said cutter head and adjustable with said head into different cutting positions about the head axis, and a motor mounted on said base and relative to which said links are swingable for actuating said kerf cutter and for swinging said links relative to said base.

78. In a mining apparatus, a portable base, parallel links pivotally connected to said base to swing in a vertical direction relative thereto, a frame supported by said links, a cutter head mounted on said frame for rotation relative thereto about a horizontal axis, a kerf cutter pivotally mounted on said cutter head and adjustable with said head into different cutting positions about the head axis, and devices for angularly adjusting the cutter head axis relative to said links.

79. In a mining apparatus, a portable base, a parallel link structure pivotally connected to said base to swing in a vertical direction relative thereto, a frame supported by said link structure, a cutter head mounted on said frame for rotation relative thereto about a horizontal axis extending longitudinally of the apparatus, a kerf cutter pivotally mounted on said cutter head, a motor on said base relative to which said link structure is swingable, and mechanism driven by said motor for adjusting said parallel link structure to move said cutter head into different operative positions while said head axis is always maintained parallel to a common straight line.

80. In a mining apparatus, a portable base, parallel links pivotally connected to said base to swing in a vertical direction relative thereto, a frame supported by said links, a cutter head mounted on said frame for rotation relative thereto about a horizontal axis, a kerf cutter pivotally mounted on said cutter head, said parallel links maintaining said cutter head axis always 110 parallel to a common straight line during swinging of said links about their pivots, and devices for tilting said cutter head about a transverse axis relative to said links to move the head axis out of parallelism with aforesaid straight line.

81. In a mining apparatus, a portable support, parallel links pivotally connected to said support to swing in a vertical direction relative thereto, a frame supported by said links, a cutter head mounted on said frame for rotation relative thereto about an axis disposed at right angles to the axes of swinging movement of said links, and a kerf cutter pivotally mounted on said cutter head, said parallel links maintaining said cutter head axis always parallel to a common straight 125 line during swinging of said links about their pivots.

82. In a mining apparatus, a portable base, parallel links pivotally connected to said base to swing in a vertical direction relative thereto, a frame supported by said links, a cutter head mounted on said frame for rotation relative thereto about an axis disposed at right angles to a line parallel to the axes of swinging movement of said links, an elongated kerf cutter pivotally mounted on said cutter head for swinging movement relative thereto and adjustable with said head as the latter is rotated into different cutting positions about the head axis, and a motor mounted on said base and relative to 135 which said links are swingable for actuating said kerf cutter.

83. In a mining apparatus, a portable base, parallel links pivotally connected to said base to swing in a vertical direction relative thereto,

- a frame supported by said links, a cutter head mounted on said frame for rotation relative thereto about an axis disposed at right angles to a line parallel to the axes of swinging movement of said links, a kerf cutter pivotally mounted on said cutter head and adjustable with said head into different cutting positions about the head axis, and a motor mounted on said base and relative to which said links are swingable for actuating said kerf cutter and for swinging said links relative to said base. 80
84. In a mining apparatus, a portable base, a parallel link structure pivotally connected to said base to swing in a vertical direction relative thereto, a frame supported by said link structure, a cutter head mounted on said frame for rotation relative thereto about an axis disposed at right angles to a line parallel to the axes of swinging movement of said links, a kerf cutter pivotally mounted on said cutter head, a motor on said base relative to which said link structure is swingable, and mechanism driven by said motor for adjusting said parallel link structure to move said cutter head into different operative positions while said head axis is always maintained parallel to a common straight line. 90
85. In a mining apparatus, a portable base, an arm structure pivotally mounted on said base to swing in a vertical direction relative thereto, a cutter support rotatably mounted on the outer extremity of said arm structure, a kerf cutter pivotally mounted on said cutter support to swing relative thereto and adjustable with said cutter support about the support axis into horizontal and vertical cutting positions, means for rotating said cutter support about its axis relative to said arm structure, means for swinging said kerf cutter relative to said cutter support, means for tilting the kerf cutter about an axis distinct from the arm structure pivot axis, from said support axis, and from the axis of kerf cutter swing and lying in an upright plane extending transversely of the arm structure to maintain the kerf cutter, when swinging of the arm structure is initiated with the kerf cutter in aforesaid horizontal cutting position in a horizontal position irrespective of the adjusted position of the arm structure about its axis, and means for swinging said arm structure relative to said base. 95
86. In a mining apparatus, a portable base, an arm structure pivotally mounted on said base to swing in a vertical direction relative thereto, a cutter support rotatably mounted on the outer extremity of said arm structure about an axis at right angles to a line parallel to the axis of pivotal movement of said arm structure, a kerf cutter pivotally mounted on said cutter support to swing relative thereto and adjustable with said cutter support about the support axis into horizontal and vertical cutting positions, means for rotating said cutter support about its axis relative to said arm structure, means for swinging said kerf cutter relative to said cutter support, means for tilting the kerf cutter about an axis distinct from the arm structure pivot axis, from said support axis, and from the axis of kerf cutter swing and lying in an upright plane extending transversely of the arm structure to maintain the kerf cutter, when swinging of the arm structure is initiated with the kerf cutter in aforesaid horizontal cutting position in a horizontal position irrespective of the adjusted position of the arm structure about its axis, and means for swinging said arm structure relative to said base. 100
87. In a mining apparatus, a portable base, an arm structure pivotally mounted on said base for swinging movement relative thereto, said arm structure extending longitudinally in advance of said base, a support pivotally mounted on the outer extremity of said arm structure for swinging movement relative thereto about an axis parallel with the arm structure axis, a cutter head mounted on said support for rotation relative thereto about an axis extending perpendicularly to said support axis, and a kerf cutter pivotally mounted on said cutter head for swinging movement relative thereto about an axis at right angles to the head axis, said kerf cutter being disposable, by head rotation exclusively, to cut parallel horizontal or parallel vertical kerfs. 105
88. In a mining apparatus, a portable base, an arm structure swingable vertically relative to said base in upright planes extending longitudinally of said base, a support pivotally mounted on said arm structure to swing relative thereto in upright planes extending longitudinally of said base, a cutter head rotatably mounted on said swingable support and rotatable relative thereto to position a kerf cutter for cutting in upright planes extending longitudinally of said base or in horizontal planes extending longitudinally of said base, and a kerf cutter pivotally mounted on said cutter head and swingable relative to the latter on an axis distinct from the axes of the other movements specified. 115

CERTIFICATE OF CORRECTION.

Patent No. 1,932,596.

October 31, 1933.

CHARLES F. OSGOOD.

It is hereby certified that error appears in the printed specification of the above numbered patent requiring correction as follows: Page 5, line 60, claim 20, strike out the word "transverse"; page 6, line 33, claim 30, for "a horizontal axis" read horizontal axes; and line 43, claim 31, strike out the article "a" first occurrence; page 7, line 1, claim 40, after "directions" insert a comma; page 10, line 143, claim 82, after each of the words "head" and "rotated" insert a comma; page 11, lines 46 and 93, claims 85 and 86 respectively, before "in" insert a comma; and line 46, claim 85, for "irrespective" read irrespective; and that the said Letters Patent should be read with these corrections therein that the same may conform to the record of the case in the Patent Office.

Signed and sealed this 30th day of October, A. D. 1934.

Leslie Frazer

(Seal)

Acting Commissioner of Patents.
